UNITED STATES PATENT OFFICE

2,565,048

CAN OPENER

Thomas L. Rush, Cleveland, Ohio

Application May 4, 1949, Serial No. 91,340

3 Claims. (Cl. 30—9)

1

The present invention relates to can openers of the type designed to remove the entire top of a can, which openers generally include a blade and a rotary toothed disk cooperating therewith and arranged to effect gripping and feeding of the edge of a can between the blade and the disk.

The primary object of the invention is to provide a simple, highly efficient can opener of the type referred to above which principally consists of two cooperating members, a blade-carrying stationary member and a rotary-disk-carrying shiftable member supported by and coupled with said base member for limited pivotal movement with respect thereto.

Another object of the invention is to provide a simple, highly efficient can opener of the type referred to above, which includes cooperating members pivotally coupled with each other for limited pivotal movement with respect to each other, each one of the cooperating members including guiding and locating means adapted to properly locate and guide a can prior to and during can opening operations.

A further object of the invention is to provide a simple and highly efficient can opener of the type referred to above, which includes cooperating members pivotally coupled with each other for limited pivotal movement with respect to each other, the members being additionally yieldingly coupled with each other by spring means arranged to yieldingly shift the members to a predetermined position with respect to each other.

With the above and additional other objects in view, the invention has other marked improvements and superiorities which radically distinguish it from presently known structures. These improvements, embodying certain novel features of construction, are more clearly set forth in the appended claims; and a preferred embodiment of the invention is hereinafter shown with reference to the accompanying drawings forming part of the specification.

In the drawings:

Fig. 1 is a side view of a can opener constructed in accordance with the invention, the view showing the can-engaging side of the opener;

Fig. 2 is a view similar to Fig. 1 but showing the pivotally supported, shiftable member shifted against the tension of a spring member to the position necessary for permitting inserting of the edge of a can between the blade and the rotary toothed disk;

Fig. 3 is a cross-sectional view through Fig. 1, the section being taken on line 3—3 of said Fig. 1;

2

Fig. 4 is a plan view of the can opener shown in Fig. 1;

Fig. 5 is a side view of the blade-carrying base member; and

Fig. 6 is a side view of the rotary-disk-carrying shiftable member.

Referring now more particularly to the accompanying drawings which illustrate a preferred embodiment of the invention, reference numeral 10 2 denotes an elongated base plate adapted to be removably supported by a U-shaped bracket 3. Base plate 2 includes near its one end a partly slotted pin member 4 which is sleeved with its slotted portion 5 on the base plate and secured thereto in any suitable manner. Pin member 4 includes a downwardly extended portion 6 which acts as a pivot arm and non-rotatably supports base plate on bracket 3 when portion 6 is extended through bores 7 in arms 8 and 20 of bracket 3 and edge 10 of base plate 2 is extended through one of several slots 11 in arm 8 arranged in diametrical relation with respect to its bore 7. The base plate has its other end enlarged and shaped to include an axially inclined boss 12 which supports a threaded pin 13 freely rotatably mounting a cone-shaped cutting blade 14. Base plate 2 furthermore pivotally supports a friction wheel supporting shiftable plate 15 which is connected to said base plate by a pivot pin 16 extended through a hole 17 at the upper end of said plate. The shiftable plate 15 rotatably mounts a friction wheel 18 secured to a shaft 19 which mounts on its other end a crank arm 20 arranged in spaced relation with respect to plate 15 by a spacer member 21.

As shown, friction wheel 18 and crank arm 20 are positioned at opposite sides of the can opener; that is, friction wheel 18 is positioned at the front side of shiftable plate 15 and crank arm 20 is positioned at the rear side of base plate 2, an arrangement necessitating extension of shaft 19 through the two plates 15 and 2. To that effect base plate 2 is formed with an arcuate slot 22 having the spacer member 21 on shaft 19 disposed therein. This construction limits the movements of plate 15 with respect to plate 2 but permits all movements necessary for proper operative positions of friction wheel 18 with respect to rotary blade 14.

The friction wheel supporting plate 15 is yieldingly shifted toward the right to position such wheel in proper working relation with respect to cutting blade 14. This is effected by a curved wire spring 23 pivotally mounted on a pin 24 arranged adjacent to pivot pin 16. Wire

spring 23 has its one end formed with an eye 25 held by pin 24 and engages the curved edge of shiftable plate 15, thus tending to shift the friction-wheel-supporting plate into proper working position with respect to the rotary cutting wheel 14.

A guard 26 in the form of a flange on friction-wheel-supporting plate 15 protects the side walls of a can from contact or engagement with the side of friction wheel 18. In addition shiftable plate 15 has its central portion shaped to a finger-like member 27 extended laterally at substantially right angle to said plate, which member locates the top of a can with respect to the friction and cutting wheels. This finger member is formed as an integral part of shiftable plate 15 and guides the can to properly feed the edge thereof between rotary blade 14 and friction wheel 18. Finger-like member 27 cooperates with a second guard 28 attached to the base plate 2 in properly locating the can when actuated upon during can-opening operations.

In cutting operations, the top of the can has been punctured when friction wheel 18 has reached proper working position with respect to cutting blade 14 and friction wheel 18 has been located below the edge of the can bead. In this position the can is slightly canted as guard 26 rests against the side wall of the can to prevent rubbing of the side wall on the friction wheel. In cutting operations the cut edge of the cover of the portion adjacent to its rim is tightly pressed against the inner margin of the can to eliminate rough edges on the opened can.

Having thus described my invention what I claim is:

1. In a can opener a base plate including a downwardly curved slot, a cutting wheel pivotally mounted on said base plate above said slot, a shiftable, crescent-shaped, friction-wheel-supporting member pivoted at one end to said base plate at a point above said cutting blade, a friction wheel assembly including a friction wheel, a pin mounting at its one end said friction wheel and freely rotatably extended through a bore in said shiftable member and the

slot in said base plate and a handle member secured to the extended end of said pin, and guide portions laterally extended from the central part and the free end of the shiftable member adapted to properly guide a can to said friction wheel and guard the side of such can from engaging the friction wheel.

2. In a can opener a base plate including a downwardly curved slot, a cutting wheel pivotally mounted on said base plate above said slot in inclined relation with respect to said plate, a shiftable, crescent-shaped member pivoted with its one end to said base plate at a point above said cutting wheel, a friction wheel assembly freely-rotatably supported by said shiftable member, said friction wheel assembly including a friction wheel mounted on a pin extended through a bore in said shiftable member and the slot in said base plate and limiting movement of said shiftable member with respect to said base plate, and a guide portion laterally extended from the central part of said shiftable member, said guide portion extending opposite said friction wheel when the can opener is operated.

3. A can opener as described in claim 2 including a curved wire spring having one end secured to the base plate and containing with its curved portion the peripheral edge of the crescent-shaped shiftable member to yieldingly hold same in proper position with respect to the cutting blade.

THOMAS L. RUSH.
